(57) **CLAIM**

The ornamental design for a monitoring device for inhaler, as shown and described.

DESCRIPTION

FIG. 1 is a perspective view of a monitoring device for inhaler showing the design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The features shown in broken lines in FIGS. 1, 2, 4, 5 and 7 depict portions of the monitoring device for inhaler that form no part of the claimed design.

In the figures, the thin diagonal lines represent translucency in a portion of the article.
